LOUIS STEINBERGER, OF NEW YORK, N. Y.

MOUTHPIECE FOR TRANSMITTERS.

1,124,547.

Specification of Letters Patent. Patented Jan. 12, 1915.

Application filed October 18, 1910. Serial No. 587,719.

To all whom it may concern:

Be it known that I, LOUIS STEINBERGER, a citizen of the United States, and a resident of the city of New York, borough of Brooklyn, in the county of Kings and State of New York, have invented a new and Improved Mouthpiece for Transmitters, of which the following is a full, clear, and exact description.

10 My invention relates to mouthpieces for transmitters, and the particular purpose thereof is to improve the acoustical properties of the device in its combination with the transmitter diaphragm by forming and disposing the parts so as to concentrate, to a marked degree, the full volume of sound waves, produced by the vibration of the vocal chords in speech, in front of the vibratory center of the transmitter diaphragm, 15 and there, approximately within a quarter of an inch of the surface of the diaphragm suddenly expanding them to some degree and yet holding them to a relatively small central area of the diaphragm, in much the 20 same manner as if the lips of the person talking were held in close unchanging proximity to the diaphragm, except that the portions of my device, corresponding to the lips, are somewhat smaller than lips and are 25 circular so as to more effectively direct the sound waves into contact with the most sensitive or central portion of the diaphragm.

A further object is to increase the mechanical strength of the mouthpiece.

30 To these ends I make the entire mouthpiece comparatively thick and massive and provide it with a single central sound passage of greatly constricted diameter at its inner end, and with an abruptly flaring compartment into which the constricted end of 35 said sound passage merges, said compartment being of substantially hemispherical shape and being disposed so that its walls extend abruptly radially in all directions 40 beyond the constricted portion of sound passage, and curve thence more and more toward the diaphragm about a central point located just slightly behind the rear face of 45 the center of the diaphragm. The opening 50 of the compartment toward the diaphragm is thus of a size to cover only a relatively small portion of the diaphragm, preferably about one-third its diametrical dimension. This relatively small portion of the dia-

phragm, being central, vibrates almost uniformly throughout its area with a maximum degree, or puretoned vibration; while the parts of the diaphragm nearer its periphery serve as a sort of spring support for the vibratory central portion. It has been 55 determined that sound waves, when led into direct contact with this outer portion, lose their identity and strength and materially interfere with the purer toned vibrations of the central portion, and are responsible, to 60 a considerable degree, for the subdued, far-away sound present in the usual telephone conversation.

By providing my hemispherical chamber with smooth, uninterrupted walls opening 70 before only the central portion of the diaphragm and having its large annular edge brought into close proximity to the surface of the diaphragm for defining the pure 75 toned vibratory central portion of the diaphragm, and by having my sound passage entering it through a greatly constricted central passage, I am enabled to retain nearly the full force of the voice concentrated upon 80 the central portion of the diaphragm.

85 Among the several advantages sought to be attained by my invention are the following: I. To provide the mouthpiece with a small compartment as above described, having the still smaller portion of said sound 90 passage merging thereinto, and to form these parts in a single integral body adapted to be attached to the ordinary phone structure in common use. II. To provide, directly around the compartment mentioned, 95 a reduced threaded portion for holding the mouthpiece firmly in position, and to form an annular shoulder disposed preferably substantially in a plane coinciding with the junction of said compartment and said sound passage, said shoulder being formed at one end of said threaded portion and serving to retain the mouthpiece so that the hemispherical compartment therein will occupy its proper position relatively to the 100 diaphragm as above defined. III. To provide a mouthpiece of the type above specified with an annular rim integral with it in order to further increase its mechanical strength, and at the same time to give it a 105 more artistic design.

Reference is to be had to the accompanying drawings forming a part of this speci-

fication, in which similar characters of reference indicate corresponding parts in both the figures.

Figure 1 is a substantially central vertical sectional view through my improved mouthpiece mounted in position as part of a transmitter, this view being slightly enlarged beyond the normal size of the parts in practice; and Fig. 2 is an inverted plan or rear view of the mouthpiece removed from the transmitter.

The transmitter casing is shown at 3 and the face plate of the transmitter at 4, this face plate being provided with a raised bead 5.

At 6 is the body member of the mouthpiece having generally a flaring form and provided at its outer end with rim 7 integral with it and made thick and massive in order to possess considerable mechanical strength. The body member 6 is provided with a reduced threaded portion 8 producing an annular shoulder 9 at the outer end of said reduced threaded portion. The body member 6 is further provided with a compartment or chamber 10 having a substantially hemispherical wall, the lower boundaries of which are coincident with the end of said body member. The body member is provided with a single sound passage which has a very great diameter at its outer end and which tapers inwardly, and terminates in a decidedly constricted portion 12 at the point where it enters the hemispherically formed chamber 10. The walls of this sound passage, lengthwise of the same, are preferably formed on curves which are substantially coincident with arcs of circles, the centers of which lie in a plane common with that of the point of juncture of the sound passage 11 and the hemispherically formed chamber 10, so that the walls of the smaller portion of the sound passage, for a short distance before they reach the chamber 10, stand nearly parallel, producing a sort of tube or nozzle which projects the sound waves more or less directly toward the central portion of said chamber, only to be scattered as they abruptly enter said chamber.

At 13 is the diaphragm which is mounted by aid of a gasket 14 in the transmitter casing 3.

At 15 is a nut carried by the diaphragm 13 and connected with the carbon pocket 16. The nut 15 is for the purpose of holding the carbon pocket relatively to the diaphragm 13 and extends slightly into the hemispherical compartment 10.

My purpose in forming a single sound passage 11 and in giving said sound passage the shape indicated, is to concentrate the sound waves in the portion 12 so as to give said sound waves the greatest possible intensity as they enter the chamber 10. My

purpose in rendering the chamber 10 substantially hemispherical is to enable the sound waves, in proceeding from the portion 12 of the sound passage 11, to spread out abruptly before reaching the diaphragm and to be reflected from the smooth uninterrupted curved dome-like walls into concentrated effect upon the pure toned vibratory central portion of the diaphragm.

I have made the discovery that the total effect of the sound waves upon the diaphragm can be qualified greatly by shaping the body member 6 as shown and described. In other mouthpieces, where the body portion is merely a hollow shell of substantially cylindrical form, the sound waves interfere with each other very greatly and tend to destroy each other. The fundamental tones, and the various overtones, become intermingled and produce a faulty vibration of the diaphragm which consequently destroys the distinctness, so lamentably missing from present day telephones. This is especially true where the structure is such as to leave any material portion of the diaphragm exposed to influence of directly projected sound waves, as has been above set forth.

In the combination of sound carrying parts illustrated in the structure shown, interference of the sound waves is in great measure avoided. The abruptness of entering the chamber 10 so scatters the waves, and the smooth curved walls of the chamber so direct them, that they are largely prevented from reaching and wasting their energy upon, and producing false vibration of, portions of the diaphragm beyond the compass of the chamber, leaving those parts practically unaffected, except in a purely mechanical sense, as a support for the pure toned vibratory central portion. For emphasizing the point involved, note that if the sound passage 11 were made of larger diameter in its portion 12, so that its inner end was, say, of the size of the large opening of the chamber 10, that the chamber were eliminated, and that the walls of the passage continued uninterruptedly outwardly from the present base of the chamber adjacent the surface of the diaphragm with no appreciable or pronounced reduction in the size of the passage, with no distinct shoulder for scattering the waves; the waves would be concentrated to a degree and would reach the inner end of the passage in their direct and uninterrupted force. A material part of them, being there first released, would migrate toward the less sensitive peripheral portion of the diaphragm and interfere with the intended mechanical function of those portions, preventing true vibration of the central part, and thus detract materially from the acoustical properties of the device. On the other

hand; if the greatly restricted passage 12 were continued, with the elimination of the chamber 10, the area of the diaphragm affected would be entirely too small, so that 5 sound waves migrating beyond it over the diaphragm would render the resultant waves unintelligible. Again, if the chamber 10 were enlarged so as to define a decidedly greater central portion, or all of 10 the diaphragm, much the same result would be obtained as in the first instance, though to a more marked degree, the well defined central portion for receiving and transferring the purer vibrations would be entirely 15 lacking, and the consequent interference between the relatively weak and the relatively strong waves impressed upon, and emanating from, the peripheral and central portions, respectively, would be unrestrained. 20 The formation of sound carrying parts, as I have arranged them, however produces a maximum effect upon a desirable extent of the sensitive central portion of the diaphragm and greatly reduces the tendency 25 of the waves to migrate radially therefrom, so that the central portion of the diaphragm will vibrate in true resonance to the parent waves entering the mouthpiece. The migrating waves which succeed in reaching the 30 peripheral portions of the disk beyond the confines of the chamber 10, are of insufficient intensity to, of themselves, cause any material vibration of those parts.

The foregoing facts, taken collectively 35 and with the showing in the drawings, indicate that the combination, and the relative proportions of the sound carrying parts, with the diaphragm, as assembled in my improved mouthpiece, preserve all the 40 strength and volume of the sounds. By the proper distribution of the sound waves from a single proximate point to a rather small area near the proximate center of the diaphragm, I preserve the overtones in a 45 fair degree. The net result is that my improved mouthpiece both preserves the volume of the sounds and maintains the true value of sounds of various kinds.

I do not limit myself to the precise construction shown, for it will be seen that the 50 essential characteristic of my invention is a greatly constricted sound passage, continuing from a wide flaring open end, and abruptly entering a dome-shaped chamber, 55 said chamber itself being of only sufficient size, at its large open end, to encompass a relatively small, highly sensitive, portion of the diaphragm; the constricted passage abruptly entering the chamber, and the relation of the chamber to the diaphragm effectively preventing deprecatory migration 60 of sound waves toward the periphery of the diaphragm. Neither do I limit myself to any particular material to be used in the 65 construction of the mouth-piece, though I

prefer to employ for this purpose the material known generally in commerce as "electrose".

It is intended that the term—greatly constricted—, as used in this specification 70 and claims to describe the sound passage 11 entering the chamber 10, shall be construed to mean a passage of a decidedly smaller diameter than that ordinarily found in telephone transmitter mouthpieces. The wide 75 open inner end of the chamber 10 is intended to be, itself, of approximately the diameter of the ordinary sound passage.

Having thus described my invention, I claim as new and desire to secure by Letters 80 Patent:

1. The combination with a telephone transmitter mechanism of usual construction comprising an apertured front wall and a diaphragm supported behind said front wall 85 substantially concentric with the aperture thereof, the diameter of the diaphragm being considerably greater than that of the aperture, of a separately formed detachable mouthpiece having a part fitted into said 90 aperture and extending therethrough into close proximity with the outer surface of the diaphragm, said part being hollowed out on its rear surface to form a hemi-spherical expansion chamber having uninterrupted 95 and smooth walls terminating in close proximity to the surface of the diaphragm so as to encompass a central, sensitive, portion of the diaphragm relatively smaller than the portion defined by the aperture of the front 100 wall, and the mouthpiece being further formed with a single greatly constricted sound passage opening substantially centrally through the wall of the hemi-spherical chamber so that said wall extends 105 abruptly radially in all directions from the end of said sound passage, and said sound passage continuing outwardly into a wide flaring open end, the walls of said greatly 110 constricted sound passage being formed on curves struck from centers substantially on the plane of the juncture of the sound passage with the expansion chamber so that portions of said sound passage nearest said chamber are nearly parallel for giving a 115 nozzle like shape to said sound passage, tending to project sound waves therefrom toward the center of the chamber, substantially as and for the purposes set forth.

2. As an article of manufacture, a mouth-piece for telephone transmitters comprising, 120 a body of material having a reduced annular threaded extension at one side thereof, adapted for detachable engagement in the threaded aperture of a telephone transmitter casing, said extension being hollowed out to form a concaved expansion chamber substantially entirely within the extension having uninterrupted and smooth walls terminating adjacent the annular edge of the ex- 130

tension, and said body of material being further formed with a single greatly constricted sound passage extending through the main portion thereof and opening into the expansion chamber, so that the wall of said chamber extends abruptly radially in all directions from the end of the sound passage.

In testimony whereof I have signed my name to this specification in the presence of two subscribing witnesses.

LOUIS STEINBERGER.
